Inventor:

Francis H. Richards.

UNITED STATES PATENT OFFICE.

FRANCIS H. RICHARDS, OF SPRINGFIELD, MASS., ASSIGNOR OF ONE-HALF
TO THE PRATT & WHITNEY COMPANY, OF HARTFORD, CONN.

MECHANICAL MOVEMENT.

SPECIFICATION forming part of Letters Patent No. 340,247, dated April 20, 1886.

Application filed October 29, 1885. Serial No. 181,212. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Mechanical Movements, of which the following is a specification.

This invention relates to mechanical movements for actuating slides, the object being to provide a mechanism adapted to operate a pair of slides in the manner hereinafter set forth.

To this end the invention consists in the combinations hereinafter described and claimed.

In the drawings accompanying and forming a part of this specification, Figure 1 is a side view of a mechanical movement embodying my invention. Fig. 2 is a top view of 20 the same. Figs. 3, 4, 5, 6, and 7 are diagrams illustrating the operation of the mechanism.

Similar characters designate like parts in all the figures.

25 The several operative parts of my newly-invented mechanical movement are supported by a simple frame-work, A. This frame has bearings for the driving-shaft S, carrying a cam, C, adapted to impart a vibratory motion to a lever, L, which is pivoted at 3 to said frame. The lever L is furnished with the usual roller, 2, running against cam C, and with a spring, 11, for moving it toward the cam. It is also furnished with another 30 roller, (or pin,) 4, which works against the cam-arm 5 of the angle-lever N, whose other arm, 6, is connected by link 7 to the short-stroke slide D. The angle-lever is pivoted on a stud, 8, fixed in the frame. It is operated in one direction by the roller 4 and in the other by spring 9. Lever L is connected by link 10 to the long-stroke slide B, which, as well as slide D, is held in place by cap 12. Arm 5 is formed at about the middle of one 45 side into a cam, 15, which is so shaped as to impart when operated by roller 4 a movement through the rocker and link 7 to slide D only during the middle part of the stroke of lever L. This particular mode of operation will be fully understood from the series 50 of diagrams Figs. 3 to 7. In Fig. 3 both slides

stand at the same end of their respective strokes, corresponding, as shown, to one of the reference-lines *a a*. The roller 4 now stands at some distance from cam 15. On now 55 swinging lever L on pivot 3 slide B is moved forward (upward in the drawings) and the roller 4 is brought close to cam 15, as shown in Fig. 4, where slide D is shown in the same position as before. On continuing the motion of lever L roller 4 acts on cam 15 to move slide D simultaneously with the movement of slide B. In Fig. 5 the parts are shown as situated when slide D is at mid-stroke; in Fig. 6, as situated when it has completed its 65 stroke. In Fig. 7 they are shown as when slide B has moved still farther to the end of its stroke, slide D remaining as in Fig. 6. Thus, as I have described, there are two slides, 70 B and D, the first operated directly and the last indirectly from the same lever L, slide B having a long stroke and slide D a short stroke begun and completed during the stroke of said slide B.

It will be understood that other means than 75 cam C, as, for instance, an ordinary crank and connecting rod, may be employed for operating lever L; also, that the proportions of the several parts are capable of modification in various ways and degrees, after the manner 80 of machines in general, without departing from the spirit of my invention.

In another application, Serial No. 153,234, filed January 19, 1885, I have shown this my present invention operating as a part of a 85 machine for packing and banding envelopes; but it is capable of other applications.

Having thus described my invention, I claim—

The combination, in a mechanical movement, of a pair of slides, as B D, lever L, connected to slide B and having a roller or pin, 4, a cam-arm pivoted substantially as described and operated by said roller or pin, connections from said arm to slide D, and actuating mechanism, substantially as described, operating lever L, substantially as set forth. 90 95

FRANCIS H. RICHARDS.
